UNITED STATES PATENT OFFICE.

ELIAS HOXIE, OF RED CREEK, NEW YORK.

HARNESS-BUCKLE.

SPECIFICATION forming part of Letters Patent No. 297,802, dated April 29, 1884.

Application filed January 29, 1884. (No model.)

To all whom it may concern:

Be it known that I, ELIAS HOXIE, a citizen of the United States of America, residing at Red Creek, in the county of Wayne and State 5 of New York, have invented certain new and useful Improvements in Harness-Buckles, of which the following is a specification, reference being had therein to the accompanying drawings.

- 10 This invention has reference to improvements in harness-buckles; and it consists of the detailed construction and disposition of parts, substantially as hereinafter set forth, and pointed out in the claim.
- 15 In the accompanying drawings, Figure 1 is a plan view of my improved buckle and its appendage as applied for use. Fig. 2 is a side elevation of my buckle. Fig. 3 is a detailed view of the appendage or appliance for 20 the buckle, and Fig. 4 is a longitudinal section of my improvement.

In the embodiment of my invention I employ a buckle with its frame A in every respect the same as the general form of harness-buckle frames, the distinctive feature of the buckle consisting in forming the tongue B with a bend or curve, B', said bend or curve forming a hook at its outer free end. This hook, as will be seen by reference to the drawings, extends over the forward end of the frame A and down through an aperture or hole in the strap to which the buckle may be applied, as shown, it having been previously, however, passed through the strap within the frame A, whereby the tongue is possessed of two points of bearing on the strap, and is therefore not liable to tear or distend the tongue-holes, while it prevents the catching of the hair of the animal's mane or tail or the net covering the horse in the buckle or by the tongue.

C is an appliance which consists of a spring-

metal or wire hook or clasp, with its divergent portions or arms d bent inwardly at their free ends, as at d', to bear against the under or inner side of the strap within the frame of the buckle, the convergent portion of said arms crossing and bearing upon the forward cross-bar of the frame, while the extreme forward end of said arms are formed and bent into a hook, d', which enters the coincident hole or aperture in the strap to combine with the bent portions d' of said arms, which enter beneath the strap, to secure the appliance in place, which in turn secures the strap and buckle together as against the same becoming accidentally separated. Said appliance also serves as a guard to prevent the catching of anything into the buckle with which it may come in contact.

The bend or curve B' of hook B may be almost wholly omitted when the strap and buckle are so located on the horse's back as to endanger chafing of the animal, thus avoiding such chafing, and in such case the spring-hook C will be sufficient to hold the end of the hook on the same plane as the strap.

Having thus described my invention, what I claim, and desire to secure by Letters Patent, is—

In a harness-buckle, the combination, with the buckle, of a safety appliance, its forward end formed with a hook and its divergent arms provided with inwardly-projecting ends adapted to enter beneath the strap, substantially as described, and for the purpose set forth.

In testimony whereof I affix my signature in presence of two witnesses.

ELIAS HOXIE.
